Primary Examiner — Leanne Was-Englehart*Assistant Examiner* — Yelizaveta Y Masalimova(74) *Attorney, Agent, or Firm* — Andrus Intellectual Property Law, LLP(57) **CLAIM**

The ornamental design for a mid-sole cleat, as shown and described.

DESCRIPTION

FIG. 1 is a bottom isometric view of a mid-sole cleat; FIG. 2 is a bottom view thereof;

FIG. 3 is a right side view thereof;

FIG. 4 is a rear view thereof;

FIG. 5 is a left side view thereof;

FIG. 6 is a front view thereof; and,

FIG. 7 is a top view thereof.

The dot-dashed broken lines represent the environment of the claimed design and form no part of the claimed design. The even-dashed broken lines represent portions of the mid-sole cleat that form no part of the claimed design.

1 Claim, 4 Drawing Sheets(56)
